CLAIM

The ornamental design for a drink cup holder, as shown and described.

DESCRIPTION

FIG. 1 is a front, right side, top perspective view of a drink cup holder showing my new design;

FIG. 2 is a rear, right side, bottom perspective view thereof;

FIG. 3 is a front elevational view thereof;

FIG. 4 is a rear side elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, perspective view thereof showing the two cupholders in their folded-up storage positions relative to the main body structure of the drink cup holder.

The broken lines depict portions of the drink cup holder that form no part of the claimed design.
